CLAIM

I claim the ornamental design for a beverage warmer, as shown and described.

DESCRIPTION

FIG. 1 is a front-side top perspective view of a beverage warmer;

FIG. 2 is a front view of the beverage warmer of FIG. 1;
FIG. 3 is a rear view of the beverage warmer of FIG. 1;
FIG. 4 is a left view of the beverage warmer of FIG. 1;
FIG. 5 is a right side view of the beverage warmer of FIG. 1;

FIG. 6 is a top view of the beverage warmer of FIG. 1; and,
FIG. 7 is a bottom view of the beverage warmer of FIG. 1.
The broken lines in the drawings illustrate portions of the
beverage warmer that form no part of the claimed design.
